PROCESS OF HYDROGENATION

Leslie G. Jenness, Englewood, N. J., assignor to
 Intermetal Corporation, Newark, N. J., a corporation of Delaware

No Drawing. Application February 4, 1938,
 Serial No. 188,785

20 Claims. (Cl. 87—12)

This invention relates to the selective hydrogenation of glyceride oils and more particularly to a process of selectively hydrogenating glyceride oils which contain substantial quantities of fatty acid radicals having more than two double bonds to produce products having improved keeping qualities. The present application constitutes a continuation in part of my copending application Serial No. 44,635, filed October 11, 1935, which is a continuation in part of my copending applications Serial Nos. 13,973, 13,974, 13,975, and 13,976, all filed March 4, 1935.

This invention is particularly adapted for the conversion of glyceride oils having notoriously poor keeping qualities, such as soya bean oil and fish oils, into palatable liquid products having keeping qualities comparable to or exceeding those of the better vegetable oils, for example, such oils as corn, sesame, or sunflower oils. Also, the invention contemplates hydrogenating the thus treated oils to highly stable semi-solid fats of lard-like or butter-like consistency having proper physical characteristics for shortening or margarine. In order to prepare such highly stable semi-solid fats the keeping qualities must first be fixed in the oil by first preparing the highly stable liquid oil. The conditions of hydrogenation for preparing the liquid oils are, in general, different from those for converting the liquid oil into a semi-solid fat having proper physical characteristics.

Olein is the most desirable constituent of the liquid oil. I have found, however, that the composition of the product on the basis of the total fatty acid radicals present does not entirely determine keeping qualities. That is, I have found that products having substantially the same fatty acid radical content and iodine number may be prepared from the same original oil so as to have widely different keeping qualities depending upon the method of preparation. This variation in keeping qualities in oils having the same composition with respect to the total fatty acid radicals present, can only be explained on the basis that mixed glycerides are formed by the present process and that an oil having the greatest number of mixed glyceride molecules has the greatest keeping qualities.

It is, therefore, an object of the invention to provide a process of selectively hydrogenating

glyceride oils having poor keeping qualities to produce liquid oils having high keeping qualities.

Another object of the invention is to provide a process of hydrogenating liquid glyceride oils containing fatty acid radicals having more than two double bonds to produce liquid oils having improved keeping qualities. 5

Another object of the invention is to provide a process of selectively hydrogenating glyceride oils to form relatively large quantities of mixed 10 glycerides.

Another object of the invention is to provide a process for substantially completely converting unsaturates having more than two double bonds into lower unsaturates, at an early stage 15 in the process, to enable the formation of olein containing mixed glycerides in a liquid oil.

Another object is to provide a process of hydrogenating in which the hydrogenation reaction is maintained uniform throughout the body of the material being hydrogenated in order to prepare 20 liquid oils having high keeping qualities fixed therein.

Another object of the invention is to control 25 the agitation, rate of hydrogen absorption, and contact of the hydrogen with the oil so as to maintain the hydrogenation reaction uniform throughout the body of material being hydrogenated.

Another object is to provide a process of making 30 semi-solid fats, such as margarine or shortening, in which liquid glyceride oils containing fatty acid radicals are first hydrogenated to fix high keeping qualities therein while the oil is still 35 liquid and then further hydrogenated to produce semi-solid fats having the desired physical characteristics.

Another object is to provide a new liquid hydrogenated oil product having high keeping qualities. 40

A further object of the invention is to provide a process of forming highly stable semi-solid fats from said liquid oil products.

A still further object of the invention is to provide a new hydrogenated semi-solid fat product having high keeping qualities. 45

Other objects and advantages of the invention will appear in the following detailed description of my invention.

The selective hydrogenation process of the pres- 50

ent invention for the making of liquid oils having high keeping qualities is preferably carried out in a closed chamber provided with agitating means and suitable inlet and discharge passages for 5 the oil and hydrogen. An example of a suitable apparatus is that disclosed in the patent to Valentine No. 1,856,128. A suitable catalyst is employed and is mixed with the oil, the mixture is agitated while being maintained at a relatively 10 high temperature, and hydrogen gas is introduced into the chamber, preferably under pressure so as to be dissolved therein and carried throughout the body of the oil by the currents due to agitation. I have found that for selective hydrogenation 15 it is important to carry out the process under conditions of high temperature, thorough agitation, a relatively low rate of hydrogen absorption, and uniformity of hydrogenation reaction throughout the mass of oil being treated, and to 20 employ a selective catalyst. The conditions of hydrogenation must be such that unsaturates having more than two double bonds are substantially eliminated and the Wesson rancidity time of the liquid oil brought to at least 10 hours by 25 the time the iodine number has been dropped to 110.

The temperature at which the process is carried on has an important effect upon the selectivity of the hydrogenation. In general, the 30 higher the temperature, the more selective is the process toward hydrogenating the higher unsaturates and preventing the hydrogenation of olein into stearin. However, higher temperatures also favor the formation of iso-olein. For this 35 reason a catalyst which is selective not only against the formation of saturates but against the formation of iso-olein is preferably employed. The temperature of hydrogenation contemplated by this invention falls within a range from 280° 40 to 380° F. and preferably between 300° and 330° F., the optimum temperature being approximately 320° F. I have found that a slow uniform reaction throughout the mass of oil being treated is of great importance. The nature of the agitation, the amount of catalyst employed, the rate 45 of gas absorption, and the hydrogen pressure as well as the temperature during hydrogenation must be carefully correlated in order to produce a liquid oil having high keeping qualities from oils having unsaturates with more than two 50 double bonds.

An example of a suitable selective catalyst is the foraminate nickel catalyst prepared by leaching with caustic soda and reducing a precipitated and dried aggregate consisting of approximately 6NiO:CrO₃, disclosed in my copending application Serial No. 13,972, filed March 30, 1935. Another example of a suitable selective catalyst is the foraminate nickel catalyst prepared by leaching with caustic soda a dried aggregate precipitated from a solution containing nickel sulphate and aluminum sulphate, the aggregate having a molecular ratio of NiO to Al₂O₃ of approximately 13 to 1. This catalyst is also 60 disclosed in my copending application above referred to. Both of these catalysts are suitable although the former is somewhat more selective against the formation of iso-olein. Certain other catalysts, for example, those known in the trade 65 as "Formate" catalysts or "Raney" catalysts, can be employed with fairly good results. With such catalysts considerable improvement over conventionally hydrogenated oils can be obtained by 70 the present invention, but the stability of such oils does not approach that obtained when the

more selective catalysts first mentioned are employed. Any other suitable catalyst having the requisite selective characteristics may be employed.

I have further found that there are at least 5 two different types or orders of selectivity. The first is the recognized tendency of the higher unsaturates to combine with hydrogen before the lower unsaturates. The extent to which this type of selectivity may be carried appears to be 10 largely dependent upon the nature of the catalyst itself as well as the conditions of hydrogenation. The highly selective catalysts contemplated by the present invention, such as the foraminate catalysts first mentioned, even under somewhat 15 unfavorable conditions produce a much greater maximum olein content than the less selective catalysts under the most favorable conditions.

The second type of selectivity is not concerned with the relative total proportions of the various 20 unsaturates in the resulting product but appears to affect selective hydrogenation within the glyceride molecules and can be accomplished only by carefully controlling the conditions of hydrogenation. I have found that the conversion of 25 even one of the acid radicals of a normal unsaturated glyceride molecule into a radical of less unsaturation makes this molecule more stable against hydrogenation at least in the presence of 30 quantities of the lower unsaturate. Thus, if the reaction through the mass is made sufficiently 35 slow and uniform, such mixed glyceride molecules are carried away from the catalytic surface before being converted to a normal glyceride, and the normal glycerides of a given unsaturation are 40 selectively converted into mixed glycerides. These mixed glycerides are not only more stable against further hydrogenation but are also more 45 stable against oxidation and are more soluble in more stable lower unsaturates so as to be protected from oxidation than are normal glycerides having the same degree of unsaturation as the most unsaturated radical of the mixed glyceride.

By hydrogenating an oil containing glycerides having more than two double bonds under the 45 conditions of uniformity of reaction contemplated by this invention, it is possible to form a liquid oil in which all of the unsaturates having more than two double bonds have been hydrogenated and substantially all of the two 50 double bond unsaturates appear to be present as mixed glycerides. The resultant liquid oil is extremely stable and in general more stable than cottonseed oil. A stable oil can be produced even though small amounts of three double bond acid 55 radicals should remain in the oil. However, if such radicals are present in the hydrogenated oil, it tends to go "off flavor" before rancidity develops, and when rancidity does develop, the characteristic odor of the oil also develops. It 60 is, therefore, desirable to completely convert all of the radicals containing more than two double bonds to lower unsaturates. In accordance with this invention, the linolenic content of soya bean oil can be completely converted at an iodine number of 117 to 112, which is before any appreciable 65 increase in saturates occurs and while the oil is substantially as liquid as it was originally. Also in the case of fish oils, the clupanodonic acids disappear along with their "fish" odor at an 70 iodine number of approximately 120 to 130, and the three double bond acid radicals are completely converted at an iodine number at least as high as 110.

The uniform slow reaction necessary to form 75

mixed glycerides may be secured in various ways, all of which involve thorough agitation and a low rate of gas absorption.

When employing a relatively large amount of catalyst, for example, 0.2% of the weight of the oil, and relatively high hydrogen pressure, for example, 10 to 25 lbs. per square inch, any appreciable amount of splashing, in contact with an atmosphere of hydrogen, must be prevented.

10 I have found that there is a tendency for the molecules in drops of oil or spray which carry suspended catalyst, to be completely hydrogenated to lower unsaturates in the hydrogen atmosphere above the oil. This results in the formation of normal glycerides instead of the desirable mixed glycerides. Thus, under the conditions mentioned, agitation should be as intense as possible without causing splashing at the surface of the oil. An example of such agitation is 15 that produced in an apparatus similar to that shown in the patent to Valentine No. 1,856,128 having two 6-inch impellers in a tank holding approximately 160 lbs. of oil, with the oil covering the top impeller and the impellers rotating 20 at a speed just below that at which splashing occurs. A speed of approximately 300 R. P. M. was found to be suitable in a specific apparatus. By overloading the apparatus so as to bring the oil considerably above the upper impeller, it was 25 possible to somewhat increase the speed without splashing.

I have also found that the uniformity of reaction can be accomplished by using a very small amount of catalyst and a low hydrogen pressure even though splashing occurs. In certain existing commercial installations of hydrogenating apparatus, it is impossible to provide for thorough agitation free from splashing without extensive alterations in the apparatus. By using 30 a small amount of catalyst and a low hydrogen pressure, for example, .05% catalyst and a hydrogen gauge pressure of 2½ lbs. per square inch, it is possible to slow down the reaction in the spray in contact with the hydrogen atmosphere 35 above the oil until localized concentrations are avoided and the reaction proceeds at a substantially uniform rate throughout the oil.

It is also possible to overcome the rapid localized reactions due to splashing by maintaining 40 an atmosphere of an inert gas, for example, carbon dioxide, above the surface of the oil. One way of accomplishing this is to mix a small amount of carbon dioxide with the hydrogen entering the hydrogenating apparatus. By regulating the amount of hydrogen and carbon dioxide delivered to the hydrogenating apparatus, so that hydrogen is substantially all combined with the oil, and directing the mixture of gases into the lower portion of the body of oil, the 45 carbon dioxide collects above the oil and can be gradually bled therefrom to maintain the proper pressure in the conversion chamber. In this manner a relatively large amount of catalyst (.2 to .25%) and a relatively high hydrogen pressure (10 to 25 lbs. per square inch) may be employed even though the particular apparatus and rate of agitation causes violent splashing. No local rapid reactions with consequent increase in the formation of normal glycerides take place. 50 When employing the foraminant catalyst disclosed herein, the amount of catalyst suitable for different variations of the process will, in general, fall within the range of 0.2 to 0.025% by weight as disclosed in Serial No. 13,973 above 55 referred to.

In order to secure uniformity of reaction and the formation of mixed glycerides, the rate of gas absorption must be maintained relatively low. The more intense the agitation so long as there are no local rapid reactions due to splashing, the higher is the rate of gas absorption which can be employed since the partially hydrogenated molecules are more rapidly removed from the surface of the catalyst. Under given conditions of temperature agitation and amount of catalyst, the rate of gas absorption varies with the hydrogen pressure and can be conveniently expressed as the drop in iodine number per hour. It has been found that the approximate maximum rate of hydrogen absorption 10 which results in the formation of mixed rather than normal glycerides and therefore the best possible oil is a drop of 10 to 15 iodine numbers per hour dependent upon the conditions of hydrogenation. If all of the other conditions of temperature, pressure, agitation, etc., are favorable, this rate of hydrogen absorption can be exceeded and an oil having a Wesson time of at least 10 hours at 110 iodine number prepared, especially if a relatively good grade of oil is being processed. Thus rates equivalent to drops of 17 or even 20 iodine numbers per hour can sometimes be employed with other conditions favorable, if it is desired to produce only an acceptable oil 15 rather than the best possible oil. The important consideration is that the hydrogenation rate should not exceed that which will produce an oil having a Wesson rancidity time at least as great as approximately 10 hours at 110 iodine number. 20

The pressure necessary for the rate of hydrogen absorption will vary between 1 or 2 up to 50 lbs. per square inch gauge also dependent upon the other conditions of hydrogenation. I have found that the hydrogen pressure can be increased in the particular apparatus mentioned up to 50 lbs. per square inch, and probably higher and still enable an acceptable oil to be produced, by decreasing the impeller speed below the 300 R. P. M. found to be just below the 25 splashing point. It was found that a speed of 260 R. P. M. produced a rate of gas absorption of approximately 10 iodine numbers drop per hour at 50 lbs. per square inch hydrogen pressure and that a high keeping quality oil resulted. 30 Thus the higher the hydrogen pressure, the lower the intensity of agitation must be in order to maintain the required rate of gas absorption. However, the intensity of agitation must not fall below that necessary to remove partially hydrogenated molecules of a given unsaturate from the catalytic surface before they are hydrogenated to a normal glyceride if the high keeping quality oil is desired. Also the selectivity is 35 not as good as in the case of more intense agitation and lower hydrogen pressure. 40

Example I

As a specific example, 160 pounds of soya bean oil were hydrogenated at a temperature of 310° F. and a pressure varying between 10 and 25 pounds per square inch. Approximately 0.2% of the catalyst made from the 6NiO:CrO₃ aggregate was employed and the mixture thoroughly agitated in a turbo mixer unit having two 6-inch 45 impellers revolving at 300 R. P. M., at which speed practically no splashing occurred. The time of hydrogenation was one hour and forty-five minutes, and the drop in iodine number was 50 55 60 65 70 75 80 85 90 95 100 105 110 115 120 125 130 135 140 145 150 155 160 165 170 175 180 185 numbers per hour. The hydrogen pressure was varied between the above limits to maintain the reaction slow and uniform.

The composition and iodine number of the original oil and product obtained were as follows:

	Original oil	Hydrogenated liquid oil
10 Saturates.....percent.....	9.4	10.1
Olein.....do.....	33.0	53.8
Linolein.....do.....	54.7	35.1
Linolenin.....do.....	2.9	0.0
Iodine number.....	136	113

15 It will be noted that the linolenin was completely converted; the linolein content reduced from 54.7% to 35.1%; the olein content increased from 33% to 53.8%; the saturated content remained substantially unchanged; and the linolein content decreased to less than two thirds of its original content. The proportion of olein appearing as iso-olein was less than 2%, which did not interfere with the oil being liquid at room temperature. The oil was extremely palatable and improved in color and showed a rancidity test of approximately 14 hours as determined by the Wesson rancidity test at 212° F. This keeping time is superior to that of the best natural vegetable oils commercially obtainable and is even superior to some of the commercial semi-solid fats now on the market.

20 As hereinbefore stated, the method disclosed is also applicable to oils such as fish oils having even higher unsaturates than linolenin. The 25 composition of these fish oils is much more complex than that of the vegetable oils hereinbefore discussed since they contain mixtures of C₁₈, C₂₀, and C₂₂ (and possibly others) acid glycerides.

Example II

25 A sample of sardine oil was analyzed and found to contain 15 to 17% of clupanodonic acid glycerides and approximately 6% of acid glycerides containing three double bonds. A charge of 160 lbs. of this sardine oil was hydrogenated with 30 2% catalyst under the same conditions and with the same catalyst as the previous example. The iodine number of the original oil was 185, and this was reduced to 103 in approximately seven hours 35 such that the rate of gas absorption was approximately a drop of 11.7 iodine numbers per hour. In such processes all of the clupanodonic acids disappear at an iodine number of approximately 140, and the three double bond unsaturates are substantially all converted at an iodine 40 number of 110 and completely disappear between an iodine number of 103 to 107. The fishy odor of the original oil also disappears at the same time as the clupanodonic acids (about 140 iodine 45 number). This oil was entirely liquid and showed a rancidity test of approximately eleven hours at an iodine number of 110. As to the keeping qualities, therefore, this hydrogenated fish oil is considerably superior to cottonseed oil.

50 55 60 65 70 75

65 The invention is also applicable to blends of fish and soya bean oil as shown in the following example:

Example III

70 A charge of oil containing 120 pounds of neutralized and bleached sardine oil and 40 pounds of neutralized and bleached soya bean oil, forming 160 pounds of 75% fish oil and 25% soya bean oil, to which was added 2.72 pounds of completely 75 hardened neutralized and bleached sardine oil

for plasticity control, was hydrogenated in the turbo mixer of Example I with an agitator speed of 304 R. P. M. at which substantially no splashing occurred. The process was carried on at temperature of 320° F. in the presence of 0.15% nickel catalyst of the type used in Example I and at a hydrogen pressure of 5 pounds per square inch. The charge was hydrogenated from an iodine number of 165.8 to 107 at an average rate corresponding to a drop of 13 iodine numbers per hour and the resultant liquid oil had a Wesson rancidity time of 12 hours so that the Wesson time was in excess of 10 hours at an iodine number of 110.

Example IV

As an example, using inert gas, a charge of 160 pounds of 75% fish oil and 25% soya bean oil was hydrogenated at a gas pressure of 35 pounds per square inch with 0.2 nickel catalyst of the same type as that employed in Example I at a temperature of 300 to 310° F. and an impeller speed of 565 R. P. M., which was sufficient to cause intense splashing. The hydrogenating gas employed was approximately 75% hydrogen and 25% carbon dioxide and was introduced at the bottom of the converter. In a very short time the free gas space above the oil consisted practically entirely of carbon dioxide, which was gradually bled off while maintaining a gas pressure of 35 pounds per square inch. The time required to drop the iodine number from 171 to 103 was seven hours or approximately 10 iodine numbers per hour. The product was free from acid radicals containing more than two double bonds and had a Wesson rancidity time of eleven hours.

Example V

As another example in which a small amount of catalyst and low hydrogenation pressure was 40 employed to secure uniformity of reaction, a 15,000 pound batch of soya bean oil was hydrogenated in a commercial hydrogenating plant. Since it was impossible, unless alterations were made, to lower the speed of the agitating equipment below the splashing point and an inert gas was not available, a small quantity, 0.05%, of the 6NiO:CrO₃ nickel catalyst was employed and a hydrogen pressure of 2 1/2 pounds per square inch gauge maintained. The oil was brought 45 to 310° F. while mixed with the catalyst and the hydrogen introduced. A temperature of 320° F. was maintained during the major part of the conversion. A time of 1 1/2 hours was required to bring the iodine number of the oil from 136 to 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925 930 935 940 945 950 955 960 965 970 975 980 985 990 995 1000

As another example in which a small amount of catalyst and low hydrogenation pressure was 40 employed to secure uniformity of reaction, a 15,000 pound batch of soya bean oil was hydrogenated in a commercial hydrogenating plant. Since it was impossible, unless alterations were made, to lower the speed of the agitating equipment below the splashing point and an inert gas was not available, a small quantity, 0.05%, of the 6NiO:CrO₃ nickel catalyst was employed and a hydrogen pressure of 2 1/2 pounds per square inch gauge maintained. The oil was brought 45 to 310° F. while mixed with the catalyst and the hydrogen introduced. A temperature of 320° F. was maintained during the major part of the conversion. A time of 1 1/2 hours was required to bring the iodine number of the oil from 136 to 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925 930 935 940 945 950 955 960 965 970 975 980 985 990 995 1000

As another example in which a small amount of catalyst and low hydrogenation pressure was 40 employed to secure uniformity of reaction, a 15,000 pound batch of soya bean oil was hydrogenated in a commercial hydrogenating plant. Since it was impossible, unless alterations were made, to lower the speed of the agitating equipment below the splashing point and an inert gas was not available, a small quantity, 0.05%, of the 6NiO:CrO₃ nickel catalyst was employed and a hydrogen pressure of 2 1/2 pounds per square inch gauge maintained. The oil was brought 45 to 310° F. while mixed with the catalyst and the hydrogen introduced. A temperature of 320° F. was maintained during the major part of the conversion. A time of 1 1/2 hours was required to bring the iodine number of the oil from 136 to 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925 930 935 940 945 950 955 960 965 970 975 980 985 990 995 1000

The liquid oil products made from oils containing unsaturates having more than two double bonds are free from such unsaturates at an iodine number of approximately 110 or higher and they have a Wesson rancidity time of at least 10 hours at this iodine number, and, in general, have keeping and shortening values greater than any known natural glyceride oil. The keeping time is in all cases greater than that of cottonseed oil, and the oils do not revert to a product having the characteristic odor of the original oil even at rancidity. While the liquid oil products resulting from the process of the present invention when using prior catalysts such as the "Formate" 75

or "Raney" catalysts have longer keeping times than any natural liquid oil, they do not approach in keeping qualities oils produced by employing the more selective foraminic catalysts.

- 5 All of the liquid oil products of the present invention have utility as liquid shortenings, salad oils, and compounding oils, from which to make semi-solid fats. It will be noted that the solid fat content is considerably smaller than that of 10 natural oils so that a much higher yield of salad oil is obtained. Also the liquid oil of high keeping qualities must first be prepared in order to produce semi-solid fats having high keeping qualities by further hydrogenation or compounding 15 with saturated fats from other sources.

In making such semi-solid fats from the thus pretreated oils, the hydrogenation process may be carried on at a more rapid rate under conditions which result in a product of the desired 20 consistency. For example, a rate of hydrogen absorption producing a drop of 40 to 50 iodine numbers per hour has been found satisfactory in practice although a lower rate of hydrogenation may be employed. Due to the presence of 25 the mixed glycerides and the fact that high keeping qualities have been fixed in the pretreated liquid oil, any reasonably selective catalyst can be employed for this portion of the process, although the more selective catalyst, the 30 better will be the quality of the resultant fat. In practice it is preferred to use the highly selective foraminic catalysts hereinbefore mentioned. The rapid hydrogenating process may be carried out without removing the oil from the 35 pretreating converter by adding more catalyst and increasing the hydrogen pressure and agitation, or it may be carried out at a subsequent time in other apparatus. I have found that the keeping time of the semi-solid fat produced from 40 the pre-treated oil is dependent upon the keeping time of the pre-treated oil and the linolein content of the semi-solid fat. For soya bean oil, this relation may be expressed approximately by the expression $H = KL^{-\frac{1}{2}}$ where H is the Wesson 45 rancidity time of the semi-solid fat, L is the percent of linolein in the semi-solid fat and K is a constant for any particular batch of pre-treated oil. It will be noted that the keeping time of the semi-solid fat decreases with an increase 50 in linolein. For this reason pre-treated oils hydrogenated to the semi-solid state with ordinary selective catalysts are somewhat inferior to those prepared by using the highly selective catalysts since the linoleic content is somewhat higher.

55 The value of the factor K can be obtained from the semi-solid fat since H and L can be determined by test. It is equal to the Wesson rancidity time of the fat if hydrogenated to a linolein content of 1% since H is equal to K in 60 the above equation if L is equal to 1. The factor K has also been found to be a straight line function of the Wesson rancidity time of the liquid oil at 110 iodine number approximately in accordance with the expression $K = 20.7h - 118$, 65 where h is the Wesson rancidity time at 110 iodine number. Thus h can be calculated from the composition and Wesson time of the semi-solid fat.

The above relations do not hold for values of 70 h (Wesson rancidity time at 110 iodine number) substantially below 10, that is to say for values of K substantially below 90, nor for values of H (Wesson rancidity time for a semi-solid fat in the margarine or shortening range) substantially below 40. Below these values K is no

longer a straight line function of h and the pre-treated oil and semi-solid fat have no substantial resistance to reversion, indicating that these values are critical. The relations are somewhat different for fish oils but the requirement 5 that the oil must be pre-treated so as to have a Wesson rancidity time of at least 10 hours by the time the iodine number has been reduced to approximately 110 still holds.

Example VI

10

As a specific example of forming a high keeping quality semi-solid fat, the liquid hydrogenated soya bean oil resulting from the Example I and having a keeping time of fourteen hours was 15 further hydrogenated at a later time by replacing it in the same converter. The temperature was maintained at 300° F., and 0.2% nickel catalyst resulting from the 6NiO:CrO₃ aggregate was employed. The impeller speed was 565 R. P. M. and the hydrogen pressure was 25 lbs. per square inch. A time of one hour and five minutes was required to reduce the iodine number from 113 to 64.7, at which time the resultant semi-solid fat showed the following characteristics and 25 analysis:

Iodine number	64.7
Wiley melting point	°C 40.4
Congeal point	°C 29.9
Wesson rancidity time	hours 107 30
Saturates	percent 29.2
Olein	do 68.0
Linolein	do 2.8

It will be noted that the linolein content is 35 nearly 3%, yet the keeping time is very high because of a very good pre-treated oil. This linolein content can be reduced to about 1% or less by carrying on the formation of semi-solid fats at a temperature of 310° F.

40

Example VII

35

As another specific example of the formation of semi-solid fats in accordance with this invention, the liquid oil resulting from the 15,000 45 pound batch of Example V and having an iodine number of 113 and a keeping time of 16 hours was further hydrogenated at a more rapid rate without removing from the converter by adding 50 15% more of the same catalyst, increasing the hydrogen pressure to 25 pounds per square inch, and decreasing the temperature to 310° F. The hydrogenation then became more rapid, and the iodine number was reduced from 113 to approximately 65 in about one hour. A semi-solid fat 55 was produced, a sample of which, after laboratory deodorization, showed a Wesson rancidity test time of 208 hours. The product at this stage showed a Wiley melting point of 39.2° C. and a congeal point of 30.6° C. The composition 60 and iodine number were as follows:

Saturates	percent 23.5
Total olein	do 75.5
Linolein	do 1.0
Iodine number	65.2 65

Example VIII

As a further example of forming semi-solid fats, another 15,000 pound batch of soya bean oil was pre-treated under the same conditions as 70 in the above example except that the hydrogen pressure was raised to approximately 5 lbs. per square inch gauge. The pre-treated oil at 115 iodine number had a keeping time of twelve hours. It was then treated in the second stage 75

in exactly the same manner as in the previous example, the hydrogen pressure, amount of catalyst, and time of rapid hydrogenation being very nearly the same. A Wiley melting point of 38° C. and a congeal point of 29.5° C. were obtained at an iodine number of 66.7. The composition and iodine number of this product were as follows:

Saturates	per cent	22.9
Total olein	do	76.3
10 Linolein	do	.8
Iodine number		66.7

The keeping time of this product was 130 hours.

15 It will be observed that the compositions of semi-solid products of the last two examples are substantially the same but that the keeping times varied widely and the better keeping time was obtained by hydrogenating the pre-treated oil having the greater keeping time.

Example IX

As another example of making a high keeping quality semi-solid fat, 160 lbs. of Manchurian soya bean oil were pre-treated, in the apparatus employed in the first specific example given in this specification, at a temperature of 310° F. and hydrogen pressure of 10 lbs. per square inch. The impeller speed was 565 R. P. M., and 0.05% 25 nickel catalyst was employed. The iodine number was reduced from 136.5 to 110 in two hours, which is a drop of 13.5 iodine numbers per hour. The oil resulting from this pre-treatment was free from linolenin and had a Wesson rancidity time of 10 hours.

35 The above pre-treated oil was hydrogenated with .2% nickel catalyst at a hydrogen pressure of 25 lbs. per square inch, impeller speed of 565 R. P. M., and temperature of 300° F. for approximately 1 hour, at which time a semi-solid fat having the following characteristics and composition resulted:

Iodine number	69.8
Wiley melting point	° C. 38.0
45 Congeal point	° C. 28.9
Wesson rancidity time	hours 38
Saturates	per cent 25.2
Olein	do 69.4
Linolein	do 5.4

50 This example represents substantially the lower limit of semi-solid fats which can be considered to be of high keeping qualities or which have any substantial resistance to flavor reversion. The Wesson rancidity time of the liquid oil at 55 110 iodine number is just 10 hours and the Wesson time of the semi-solid fat is but 38 hours.

Example X

As another example of making a high keeping time semi-solid fat, a charge of 160 lbs. of sardine oil was hydrogenated in a converter similar to that shown in the Valentine patent above mentioned. The impeller speed was maintained at 300 R. P. M. during the pre-treatment of the oil 60 so as to prevent splashing, and .2% of the highly selective catalyst, first mentioned, was employed at a temperature of 310° F. and a hydrogen pressure of 15 lbs. per square inch gauge. The liquid oil had an iodine number of 103 and a keeping 65 time of eleven hours. The temperature was then reduced to 300° F., and the impeller speed increased to 565 R. P. M. The hydrogenation was continued until the oil had an iodine number of 70.8, at which time its Wiley melting point was 70 75 37.0° C. and its congeal point 30.1° C. This semi-

solid product was of lard or butter-like consistency and had a Wesson rancidity time of 25 hours. In general, semi-solid fats from fish oils can be produced by the present invention having an iodine number below 80, a melting point below 40° C., and a keeping time between 25 and 30 hours.

Example XI

As an example of producing a semi-solid fat from a blend of soya bean and fish oil, the liquid oil resulting from Example III was further hydrogenated in the same apparatus with an impeller speed of 565 R. P. M. with the same amount of catalyst at a temperature of 300° F. and a hydrogen pressure of 50 pounds per square inch in 15 order to give desired shortening characteristics. The iodine number was dropped from 107 to 76.6 in 1½ hours resulting in a product having a neutral flavor and color, a congeal point of 30.6° C. and a Wiley melting point of 38.4° C. The 20 Wesson rancidity time was 45 hours, which is extremely high for products containing fish oil.

It is to be noted that, even by employing one of the better prior catalysts such as the "Formate" or "Raney" catalysts in the process of hydrogenation herein disclosed, both liquid oils and semi-solid products considerably better than known products result. However, such products do not approach those made by the present process when the highly selective foraminic catalysts are employed. For example, by employing the "Formate" catalyst in the present process, the linolenin can be eliminated from soya bean oil at an iodine number of approximately 105 and with the "Raney" catalyst at an iodine number of 35 approximately 95 and a semi-solid fat having higher keeping qualities than known fats produced. However, by employing the highly selective foraminic catalysts in the pre-treating stage 40 and then the prior catalysts for the rapid hydrogenation to a semi-solid fat, a much better product can be obtained. The distinction between the prior catalysts and the foraminic catalysts is shown by the fact that even rapid hydrogenation, using this catalyst from the 45 original oil to the semi-solid fat without a pre-treating step, produces a better product than any process in which the prior catalysts are employed. By employing a pre-treating stage of hydrogenation followed by rapid hydrogenation, both with the highly selective catalyst, a product having several times the keeping qualities of any fat made by employing the prior catalysts in any 50 stage of the process results.

In the examples of oil or fat compositions given in this specification, the saturates, total olein, and linolein were determined from the thiocyanogen and the iodine numbers, both of which are obtained as a result of titration methods, are more accurate than the older methods involving fatty acid separation, and are standard methods at the present time. The iso-olein was determined by the Twitchell lead salt-alcohol method, which is a standard method at the present time. It is, of course, understood that the original oils hereinbefore described had been treated by the usual refining methods before hydrogenating and that the products of hydrogenation were submitted to the usual steam deodorization before testing for 60 edible properties. The Wesson rancidity tests were conducted under standardized conditions and checked against standard oxygen absorption tests conducted at 100° C. with an air flow of 65 2½ cc. per second with observations of the rate 70 75 80 85 90 95 98 99 99.5 100.

of peroxide formation. The Wesson rancidity tests are well known tests for determining the resistance of glyceride oils and fats to becoming rancid and were carried out as follows:

5 Absorbent cotton was cut into sheets 4 x 5 inches in size, each weighing approximately 5 grams. Two grams of the oil or melted fat were spread over the center of a sheet of the cotton. One-third of the length of the sheet was folded 10 over the top of the distributed oil or fat and the remaining third was then folded over the first one-third. The resulting strip was then rolled into a cylinder and placed in a 3½ ounce margarine jar. The cap for this jar, with the paper 15 lining thereof removed, was loosely screwed upon the jar. The jar containing the cylinder was then placed in a forced circulation electric oven held at 100° C. ± 1° C. by a thermostat control. The contents of the jar was smelled at frequent 20 intervals to detect the break down point, which is determined by the presence of a definitely rancid odor accompanied by the presence of acrolein and other aldehydes. The number of hours required to develop this rancidity point is 25 the Wesson rancidity time.

In this connection, it is noted that the best commercial semi-solid fats prepared from cottonseed oil show a Wesson rancidity time of 18 hours and an oxygen absorption test of 33 hours, 30 while the semi-solid fat prepared from soya bean oil as herein disclosed and having a Wesson rancidity time of 208 hours showed an oxygen absorption test of 425 hours, and that the rate of peroxide formation between various samples will 35 bear the same relationship as the Wesson tests.

While I have described the preferred embodiment of my invention, it is to be understood that the invention is not limited to the details thereof but may be varied within the scope of the following claims.

I claim:

1. In the process of making a semi-solid edible hydrogenated soya bean oil product, the steps which comprise, hydrogenating said soya bean oil in the presence of a selective catalyst at a temperature between 280 and 380° F., and at a hydrogenation rate not substantially greater than a drop of 15 iodine numbers per hour and with sufficient agitation to produce a substantially uniform rate of reaction throughout the oil being hydrogenated to obtain an oil having a Wesson time not less than 10 hours by the time the iodine number of the oil has been reduced to 110, and then further hydrogenating said oil in the presence of a selective catalyst to the semi-solid state thereby producing a semisolid fat characterized by having substantial resistance to reversion to the characteristic soya bean oil flavor.

2. The process of making a liquid edible hydrogenated soya bean oil which comprises, hydrogenating said soya bean oil in the presence of a selective catalyst at a temperature between 300 and 330° F., at a hydrogenation rate not substantially greater than a drop of 15 iodine numbers per hour and at a relatively low pressure and catalyst concentration and with sufficient agitation to produce a substantially uniform rate of reaction throughout the oil to obtain an oil having a Wesson time not less than 10 hours by the time the iodine number of the oil has been reduced to 110, thereby producing liquid oil having substantial resistance to reversion to the characteristic soya bean flavor.

3. The process of making a liquid edible hydrogenated soya bean oil, which comprises hy-

drogenating said soya bean oil in the presence of a selective catalyst at a temperature between 280 and 380° F., and at a hydrogenation rate not substantially greater than a drop of 15 iodine numbers per hour and with sufficient agitation to produce a substantially uniform rate of reaction throughout the oil being hydrogenated to obtain an oil having a Wesson time of not less than 10 hours by the time the iodine number of the oil has been reduced to 110, thereby producing a liquid oil having substantial resistance to reversion to the characteristic soya bean flavor.

4. In the process of making a semi-solid edible hydrogenated soya bean oil product, the steps which comprise, hydrogenating said soya bean oil in the presence of a selective catalyst at a temperature between 300 and 330° F., at a hydrogenation rate not substantially greater than a drop of 15 iodine numbers per hour and at a relatively low pressure and catalyst concentration and with sufficient agitation to produce a substantially uniform rate of reaction throughout the oil to obtain an oil having a Wesson time not less than 10 hours by the time the iodine number of the oil has been reduced to 110, and then further hydrogenating said oil in the presence of a selective catalyst to the semi-solid state, thereby producing a semi-solid fat characterized by having substantial resistance to reversion to the characteristic soya bean flavor.

5. In the process of making a semi-solid edible hydrogenated soya bean oil product, the steps which comprise, hydrogenating said soya bean oil in the presence of a selective catalyst at a temperature between 300 and 330° F., and at a hydrogenation rate not substantially greater than a drop of 15 iodine numbers per hour and with sufficient agitation to produce a substantially uniform rate of reaction throughout the oil being hydrogenated to obtain an oil having a Wesson time not less than 10 hours by the time the iodine number of the oil has been reduced to 110, and then further hydrogenating said oil in the presence of a selective catalyst to the semi-solid state, thereby producing a semi-solid fat characterized by having substantial resistance to reversion to the characteristic soya bean flavor.

6. The process of making a liquid edible hydrogenated soya bean oil, which comprises, hydrogenating said soya bean oil in the presence of a selective catalyst at a temperature between 300 and 330° F., and at a hydrogenation rate not substantially greater than a drop of 15 iodine numbers per hour and with sufficient agitation to produce a substantially uniform rate of reaction throughout the oil being hydrogenated to obtain an oil having a Wesson time not less than 10 hours by the time the iodine number of the oil has been reduced to 110, thereby producing a liquid oil having substantial resistance to reversion to the characteristic soya bean flavor.

7. In the process of making a semi-solid edible hydrogenated product from oils containing substantial quantities of fatty acid radicles having more than two double bonds, the steps which comprise, hydrogenating said oil in the presence of a selective catalyst at a temperature between 280 and 380° F., and at a hydrogenation rate not substantially greater than a drop of 15 iodine numbers per hour and with sufficient agitation to produce a substantially uniform rate of reaction throughout the oil being hydrogenated to obtain an oil having a Wesson time not less than 10 hours by the time the iodine number of the oil has been reduced to 110, and then further hydro-

generating said oil in the presence of a selective catalyst to the semi-solid state, thereby producing a semi-solid fat characterized by having substantial resistance to reversion to the characteristic flavor of the original oil.

8. The process of making a liquid edible hydrogenated oil from oils containing substantial quantities of fatty acid radicles having more than two double bonds which comprises, hydrogenating said oil in the presence of a selective catalyst at a temperature between 300 and 330° F., at a hydrogenation rate not substantially greater than a drop of 15 iodine numbers per hour and at a relatively low pressure and catalyst concentration and with sufficient agitation to produce a substantially uniform rate of reaction throughout the oil to obtain an oil having a Wesson time not less than 10 hours by the time the iodine number of the oil has been reduced to 110, thereby producing liquid oil having substantial resistance to reversion to the characteristic flavor of the original oil.

9. The process of making a liquid edible hydrogenated oil from oils containing substantial quantities of fatty acid radicles having more than two double bonds which comprises, hydrogenating said oil in the presence of a selective catalyst at a temperature between 280 and 330° F., and at a hydrogenation rate not substantially greater than a drop of 15 iodine numbers per hour and with sufficient agitation to produce a substantially uniform rate of reaction throughout the oil being hydrogenated to obtain an oil having a Wesson time not less than 10 hours by the time the iodine number of the oil has been reduced to 110, thereby producing a liquid oil having substantial resistance to reversion to the characteristic flavor of the original oil.

10. In the process of making a semi-solid edible hydrogenated product from oils containing substantial quantities of fatty acid radicles having more than two double bonds, the steps which comprise, hydrogenating said oil in the presence of a selective catalyst at a temperature between 300 and 330° F., at a hydrogenation rate not substantially greater than a drop of 15 iodine numbers per hour and at a relatively low pressure and catalyst concentration and with sufficient agitation to produce a substantially uniform rate of reaction throughout the oil to obtain an oil having a Wesson time not less than 10 hours by the time the iodine number of the oil has been reduced to 110, and then further hydrogenating said oil in the presence of a selective catalyst to the semi-solid state, thereby producing a semi-solid fat characterized by having substantial resistance to reversion to the characteristic flavor of the original oil.

11. In the process of making a semi-solid edible hydrogenated product from oils containing substantial quantities of fatty acid radicles having more than two double bonds, the steps which comprise, hydrogenating said oil in the presence of a selective catalyst at a temperature between 300 and 330° F., and a hydrogenation rate not substantially greater than a drop of 15 iodine numbers per hour and with sufficient agitation to produce a substantially uniform rate of reaction throughout the oil being hydrogenated to obtain an oil having a Wesson time not less than 10 hours by the time the iodine number of the oil has been reduced to 110, and then further hydrogenating said oil in the presence of a selective catalyst to the semi-solid state, thereby producing a semi-solid fat characterized by having

substantial resistance to reversion to the characteristic flavor of the original oil.

12. The process of making a liquid edible hydrogenated oil from oils containing substantial quantities of fatty acid radicles having more than two double bonds, which comprises hydrogenating said oil in the presence of a selective catalyst at a temperature between 300 and 330° F., and a hydrogenation rate not substantially greater than a drop of 15 iodine numbers per hour and with sufficient agitation to produce a substantially uniform rate of reaction throughout the oil being hydrogenated to obtain an oil having a Wesson time not less than 10 hours by the time the iodine number of the oil has been reduced to 110, thereby producing a liquid oil having substantial resistance to reversion to the characteristic flavor of the original oil.

13. In the process of making a semi-solid edible hydrogenated product from a mixture of soya bean and fish oils, the steps which comprise, hydrogenating said oils in the presence of a selective catalyst at a temperature between 280 and 330° F., and at a hydrogenation rate not substantially greater than a drop of 15 iodine numbers per hour and with sufficient agitation to produce a substantially uniform rate of reaction throughout the oil being hydrogenated to obtain an oil having a Wesson time not less than 10 hours by the time the iodine number of the oil has been reduced to 110, and then further hydrogenating said oil in the presence of a selective catalyst to the semi-solid state, thereby producing a semi-solid fat characterized by having substantial resistance to reversion to the characteristic flavor of the original oils.

14. The process of making a liquid edible hydrogenated oil from a mixture of soya bean and fish oils which comprises, hydrogenating said oils in the presence of a selective catalyst at a temperature between 280 and 330° F., and at a hydrogenation rate not substantially greater than a drop of 15 iodine numbers per hour and with sufficient agitation to produce a substantially uniform rate of reaction throughout the oil being hydrogenated to obtain an oil having a Wesson time not less than 10 hours by the time the iodine number of the oil has been reduced to 110, thereby producing a liquid oil characterized by having substantial resistance to reversion to the characteristic flavor of the original oils.

15. The method of producing a liquid oil having high keeping qualities from glyceride oils containing higher unsaturates than linolein, which comprises hydrogenating said oils in the presence of 0.2 to 0.025 per cent of nickel catalyst prepared by leaching chromium from and reducing an aggregate containing NiO and CrO₃ combined in a ratio of approximately 6 to 1, maintaining the temperature of the oil during hydrogenation between 280 and 330° F., agitating the oil during hydrogenation to maintain a substantially uniform reaction throughout said oil, and maintaining a hydrogen pressure on said oil sufficient to provide a hydrogen absorption rate not substantially greater than a drop of 15 iodine numbers per hour.

16. The method of producing a liquid oil having high keeping qualities from glyceride oils containing higher unsaturates than linolein, which comprises hydrogenating said oils in the presence of 0.2 to 0.025 per cent of nickel catalyst prepared by leaching aluminum from and reducing an aggregate containing NiO and Al₂O₃ combined in a ratio of approximately 13 to 1, maintaining the

temperature of the oil during hydrogenation between 280 and 380° F., agitating the oil during hydrogenation to maintain a substantially uniform reaction throughout said oil, and maintaining a hydrogen pressure on said oil sufficient to provide a hydrogen absorption rate not substantially greater than a drop of 15 iodine numbers per hour.

17. The process of making a liquid edible hydrogenated soya bean oil, which comprises, hydrogenating said soya bean oil in the presence of a selective catalyst at a temperature above 280° F. and below that at which substantial quantities of iso-olein are formed before an iodine number of 110 is reached, and at a hydrogenation rate not substantially greater than a drop of 20 iodine numbers per hour and with sufficient agitation to produce a substantially uniform rate of reaction throughout the oil being hydrogenated to obtain an oil having a Wesson time of not less than 10 hours by the time the iodine number of the oil has been reduced to 110, thereby producing a liquid oil having substantial resistance to reversion to the characteristic soya bean flavor.

18. The process of making a semi-solid edible hydrogenated soya bean oil product which comprises, hydrogenating said soya bean oil in the presence of a selective catalyst at a temperature above 280° F. and below that at which substantial quantities of iso-olein are formed before an iodine number of 110 is reached, and at a hydrogenation rate not substantially greater than a drop of 20 iodine numbers per hour and with sufficient agitation to produce a substantially uniform rate of reaction throughout the oil being hydrogenated to obtain an oil having a Wesson time of not less than 10 hours by the time the iodine number of the oil has been reduced to 110, and then further hydrogenating said oil in the presence of a selective catalyst to the semi-solid state, thereby producing a semi-solid fat characterized by having substantial resistance to reversion to the characteristic soya bean flavor.

sistance to reversion to the characteristic soya bean flavor.

19. The process of making a liquid edible hydrogenated oil from oils containing substantial quantities of fatty acid radicals having more than two double bonds, which comprises, hydrogenating said oil in the presence of a selective catalyst at a temperature above 280° F. and below that at which substantial quantities of iso-olein are formed before an iodine number of 110 is reached, and at a hydrogenation rate not substantially greater than a drop of 20 iodine numbers per hour and with sufficient agitation to produce a substantially uniform rate of reaction throughout the oil being hydrogenated to obtain an oil having Wesson time not less than ten hours by the time the iodine number of the oil has been reduced to 110, thereby producing a liquid oil having substantial resistance to reversion to the characteristic flavor of the original oil.

20. The process of making a semi-solid edible hydrogenated product from oils containing substantial quantities of fatty acid radicals having more than two double bonds, which comprises, hydrogenating said oil in the presence of a selective catalyst at a temperature above 280° F. and below that at which substantial quantities of iso-olein are formed before an iodine number of 110 is reached, and at a hydrogenation rate not substantially greater than a drop of 20 iodine numbers per hour and with sufficient agitation to produce a substantially uniform rate of reaction throughout the oil being hydrogenated to obtain an oil having Wesson time not less than ten hours by the time the iodine number of the oil has been reduced to 110, and then further hydrogenating said oil in the presence of a selective catalyst to the semi-solid state, thereby producing a semi-solid fat characterized by having substantial resistance to reversion to the characteristic flavor of the original oil.
